UNITED STATES PATENT OFFICE.

FRANZ YOKEL, OF MERIDEN, CONNECTICUT, ASSIGNOR TO THE MERIDEN BRONZE COMPANY, OF SAME PLACE.

DESIGN FOR A BASE FOR LAMPS.

SPECIFICATION forming part of Design No. 23,777, dated November 6, 1894.

Application filed October 9, 1894. Serial No. 525,436. Term of patent 3½ years.

To all whom it may concern:

Be it known that I, FRANZ YOKEL, of Meriden, in the county of New Haven and State of Connecticut, have invented a new and original 5 Design for Bases for Lamps; and I do hereby declare the following, when taken in connection with the accompanying drawing and the letters of reference marked thereon, to be a full, clear, and exact description of the same, 10 and which said drawing constitutes part of this specification and represents a perspective view.

This invention relates to a design for bases for lamps, and the design consists in the configuration and ornamentation as herein described and shown in the accompanying illustration.

The base consists of four legs, the feet of which terminate in plain scrolls A, sur- 15 mounted by upspringing leaf-like scrolls B,

overlapping wide, solid, curved bands C, which extend toward and lap upon a relief ornamentation *r*, of floriated work, uniting the legs. In the space formed by the branching of the bands C, is an oval ornamentation 25 D, surrounded by slightly foliated scrolls E. Above this ornamentation is a raised, substantially flat band F, above which rises an open scroll ornamentation G, all as shown in the accompanying illustration. 30

I claim—

The design for a base for lamps as herein described and shown.

In testimony whereof I have signed this specification in the presence of two subscribing witnesses.

FRANZ YOKEL.
